UNITED STATES PATENT OFFICE.

PERCIVAL H. ATKINSON, OF BURNS, OREGON.

ATTACHMENT FOR THE CHECK-CHUTES OF CHECK-OPERATED LOCKS.

1,266,759.

Specification of Letters Patent. Patented May 21, 1918.

Application filed September 27, 1916. Serial No. 122,458.

To all whom it may concern:

Be it known that I, PERCIVAL H. ATKINSON, a native-born citizen of the United States, residing at Burns, in the county of 5 Harney and State of Oregon, have invented new and useful Improvements in Attachments for the Check-Chutes of Check-Operated Locks, of which the following is a specification.

10 This invention relates to an attachment for the check chutes of locks which may be used upon lockers, and the like, and in which mechanism for holding the lock bolt in locked position may be rendered tempo- 15 rarily inactive through the insertion within the key check chute of a key check which was discharged from the chute upon movement of the bolt of the lock to locking position.

20 The primary object of the invention is to provide an attachment of this character which when mounted upon the lock casing not only provides an entrance to the key check chute and normally permits the in- 25 sertion within the key check chute of the key check expelled from the lock by move- ment of the lock bolt to locked position, but is so constructed that it may be operated to prevent the insertion of said key check, thus 30 rendering it necessary for the possessor of the check to obtain from the person in charge of the lockers a check by means of which the mechanism controlling the move- 35 ment of the lock bolt may be operated there- by enabling a charge to be made for the use of the locker upon which the lock is installed after a predetermined period.

Another object of the invention is to pro- 40 vide an attachment for controlling the in- sertion of a key check within the check chute in which a dial plate having a check slot therein is provided with a rotatable disk having formed therein crossed key check slots of different configuration which, 45 when the disk is turned upon the dial plate to cause either of said key check slots to register with the slot in the dial plate, will only permit a key check corresponding in shape to the key check slot in the disk which 50 is in registration with the slot in the dial plate to be passed therethrough, thereby enabling said mechanism to be operated to prevent the operation of the lock after a predetermined time by the check discharged 55 therefrom or by duplicate checks.

With these and other objects in view, the invention resides in the novel combina- 60 tion and arrangement of parts, which will be hereinafter described and particularly pointed out in the claims.

The preferred embodiment of the invention has been illustrated in the accompany- 65 ing drawings, although no restriction is necessarily made to the precise details of construction therein shown, as changes, al- 70 terations, and modifications, within the scope of the claims may be resorted to when desired.

Like characters of reference denote cor- 75 responding parts throughout the several views in the drawings, in which:

Figure 1 is a view in elevation of a locker having connected therewith a check oper- 80 ated lock to the casing of which the invention is shown applied.

Fig. 2 is a view in elevation of the at- 85 tachment and showing the same mounted upon a portion of a lock case.

Fig. 3 is a view looking at the reverse side of the attachment.

Fig. 4 is a vertical transverse section on the line 4-4 of Fig. 2.

Fig. 5 is a horizontal transverse section on the line 5-5 of Fig. 2.

Fig. 6 is a detailed view in elevation of the rotatable disk included in the check controlling mechanism.

Fig. 7 is a detailed view of the indicator ring.

Fig. 8 is a perspective view of a pair of 90 key checks for use in connection with the lock.

Referring now to the drawings in detail, the numeral 1 designates a locker upon the door 2 of which is arranged a key check op- 95 erated lock preferably constructed as shown in the United States Patent to Flowers, No. 1,180,993, the casing 4 of which is arranged in an opening in the door 2 and provided with a face plate 5 having formed therein 100 a circular opening 6 in advance of the entrance opening in a key check chute 7 adapt- ed to receive a check key 8 by means of which mechanism for controlling the lock bolt (not shown in the drawings) may be 105 operated.

Secured to the face plate 5 in any suitable manner to over-lie the circular opening 6 therein is a dial plate 9 having formed 110 therein a centrally arranged key check slot

- 10 alining with the entrance opening in the key check chute 7 and adjacent which is formed, in the plate 9, an arcuate indicator arm receiving slot 11 the length of which is approximately 150 degrees. Spaced graduations 12 formed in the dial plate 9 radiate from the slot 11 with some of the graduations having arranged adjacent thereto, suitable designating characters 13.
- 16 Arranged on the rear face of the dial plate 9 and in contact with the end of the key check chute 7, is a circular plate 14, said plate being secured to the dial plate 9 in any suitable manner and has formed in 15 the face thereof which is to contact with said plate, a centrally arranged and circular recess forming a disk chamber 15 communicating with the entrance opening in the key check chute 7 through a key check slot 16 formed in the rear face of the plate 14 and alining with the key check slot 10 in the dial plate 9.

Secured to the rear face of the plate 14 is a spring having fingers 17 which when the 25 key check 8 is passed through the slots 10 and 16 are spread apart by the key check, and serve to prevent the withdrawal of the key check after its insertion within the key check chute 7.

- 30 Arranged within the chamber 15 in the plate 14 is a disk 18 having formed upon one face thereof a centrally arranged extension 19 contacting with the rear face of the dial plate 9 and providing the disk 18 with 35 an annular bearing shoulder 20, said extension having formed therein crossed key check slots 21 and 22, the side walls of which are provided with spaced ribs 23 so that each key check slot has a different configuration and will prevent a key check which does not correspond in shape thereto from being passed through the key check slots 10 and 16.

The face of the disk 18 which confronts 45 the rear face of the dial plate 9 has formed therein a circumferential series of spaced openings 24 spaced from the periphery of the disk 18 and shoulder 20 thereon.

- 50 Mounted to turn on the shoulder 20 and over-lying the spaced openings 24 in the disk 18 is an indicator ring 25 retained on the disk 18 by the dial plate 9, said ring having formed thereon a laterally extending indicating arm 26 having formed thereon at its free end an indicating hand 27 arranged at right-angles to the arm 26 and disposed adjacent the graduations 12 on the dial plate 9, said arm having formed therein a longitudinally extending and threaded 55 opening 28.

Through the above described manner of arranging the disk 18 and indicator ring 25 within the chamber 15 in the plate 14, it will be seen that the disk 18 is freely rotatable 60 within said chamber beneath the dial plate

9 and that the indicator ring may be turned the distance of the slot 11 in the dial plate 9, on the disk 18.

To lock the indicator ring to the disk 18 so that the disk and ring may be simultaneously turned within the chamber 15 and also to afford an operating means for said members, an operating handle 29 is arranged at the free end of the indicator arm 26 and has passing therethrough a longitudinally extending channel 30 enlarged and threaded for a portion of its length, as at 31, said channel having passing therethrough a tie pin 32 one end of which is received in an opening 24 in the disk 18, the other end of the tie pin having formed thereon a channeled head 33 disposed in the enlarged portion of the channel 31 thus securing the operating handle 29 to the indicator arm and adjustably connecting the indicator ring with the disk 18.

To retain the tie pin 32 in the channel in the operating handle 29, a cap 34 is provided and has formed thereon a threaded extension 35 adapted to be received in the enlarged and threaded portion 31 of the channel 30 thus removably connecting the cap 34 with the operating handle to permit the removal of the tie pin 32 so that the position of the indicator ring 25 upon the disk 18 95 may be changed so that the key check slot 21 or 22 which previously registered with the key check slots 10 and 16 when the disk and ring were turned can not be brought into registration with the key check slots 10 and 16 when said ring and disk are turned by means of the handle 29.

When the device is in use, the indicator ring 25 is preferably connected with the disk 18 in such a manner that when one of the key check slots 21 or 22 is in registration with the key check slots 10 and 16, the indicating hand 27 will be arranged at a point intermediate the ends of the slot 11 so that a key check which corresponds in shape to the key check slot which is in registration with the openings 10 and 16 may be passed through said openings and into the key check chute 7, the slot 11 being of such length that when the handle 29 is moved in either direction, the key check slot in the disk 18 which is out of registration with the key check slots 10 and 16 can not be brought into registration with said slots unless the tie pin 32 is removed from the handle 29 115 and the disk 18 turned to cause said slot to register with the slots 10 and 16.

When the indicator ring and disk 18 are connected in such a manner that the indicator hand is arranged at a point intermediate the ends of the slot 11, one of the key check slots in the disk 18 will be in registration with the slots 10 and 16 in the dial plate and plate 14. It will be seen upon reference to Fig. 2 in the drawings that the key check 125 130

8 which corresponds to the shape of the slot in registration with the slots 10 and 16 may be passed through said slots and into the key check chute 7 and that when the handle 5 29 is moved toward either end of the slot 11, the key check slot which is in registration with the slots 10 and 16 will be moved out of alinement therewith thereby requiring the indicating hand to be again moved to a 10 position central of the slot 11 before a check can be passed through said slots.

If for any reason, it is found desirable to prevent the operation of the lock by the check which would pass through the slot 15 which is in alinement with the slots 10 and 16, the cap 34 may be removed from the operating handle 29 and the threaded end of the tie pin 32 removed from the threaded opening 24 in the disk 18 and the disk turned 20 until the other key check slot therein is brought into registration with the openings 10 and 16 at which time, the indicator ring 25 may be again locked to the disk 18 by the tie pin 32 so that when the indicator hand 25 is arranged centrally of the slot 11, the check which could previously be passed through the slots 10 and 16 will be prevented from being passed therethrough by the ribs on the walls of the slot which is in registration 30 with said openings, thereby rendering it necessary for the possessor of the check to secure an additional check from the owner of the locker before access may be had to the locker upon which the lock is installed.

35 From the foregoing description, taken in connection with the accompanying drawings, it is at once apparent that a device has been provided which when applied to a check operated lock will serve as a guard to 40 control the admission of the check within the lock.

Having thus described the invention, what is claimed as new, is:

1. The combination with the check chute 45 of a check operated lock, of a casing having check slots therein registering with the en-

trance to said check chute, a disk mounted for rotation within said casing and having crossed check slots therein, and means for causing one of said crossed check slots to 50 register with the slots in said casing.

2. The combination with the check chute of a check operated lock, of a casing having check slots therein alining with the entrance to said check chute, a disk mounted to turn 55 in said casing and having crossed check slots therein adapted to be brought one at a time into registration with the check slots in said casing, and means upon said casing and disk for indicating the position of said crossed 60 check slots.

3. The combination with the check chute of a check operated lock, of a casing having a graduated face plate provided with an arcuate slot, said casing having check slots 65 therein registering with the entrance of the check chute, a disk mounted to turn in said casing and having crossed check slots therein adapted to be brought one at a time into registration with the check slots in said casing, a ring adjustably connected with said disk and having an arm extending through the arcuate slot in said face plate, and an indicating hand on said arm. 70

4. The combination with the check chute 75 of a check operated lock, of a casing, a graduated face plate on said casing having an arcuate slot therein, said casing and face plate having check slots therein registering with each other and with the entrance to the 80 check chute, a disk mounted to turn in said casing and having crossed check slots therein adapted to be brought one at a time into registration with the check slots in said casing and face plate, a ring mounted on said disk 85 and having an arm passing through said slot, an indicator hand on said arm, and a disk operating handle passing through said arm and removably connected with said disk. 90

In testimony whereof I affix my signature. 90

PERCIVAL H. ATKINSON.
